Inventor:
Irving R. Valentine,
by *Irving R. Valentine*
His Attorney.

UNITED STATES PATENT OFFICE

IRVING R. VALENTINE, OF ERIE, PENNSYLVANIA, ASSIGNOR TO GENERAL ELECTRIC COMPANY, A CORPORATION OF NEW YORK.

ELECTRIC FURNACE.

Application filed February 26, 1925. Serial No. 11,863.

My invention relates to electric furnaces, more particularly to electric furnaces for melting metals by passing an electric current through the charge itself, and has for its object the provision of a method and means whereby higher current densities can be used and the rapidity of heating thereby increased.

In electric furnaces of this type for melting metals there is a tendency for the molten charge to be disrupted by the so-called pinch force which is incidental to the passage of an electric current through any conductor. This pinch force is due to the magnetic field surrounding the conductor, and has the effect of squeezing or constricting the conductor. Where the conductor is a liquid this force will be strong enough to rupture the circuit if the current density is high enough. When rupture of the circuit occurs the action of the furnace is intermittent and otherwise unsatisfactory. Consequently, the maximum permissible current density for satisfactory operation is limited to some value lower than that which will produce rupture of the circuit. It follows that the power input and hence the rapidity of heating are limited by the pinch effect.

In carrying out my invention I provide an auxiliary reservoir of molten charge which is connected with the current carrying portion of the charge and serves to supply molten charge to prevent rupture by the pinch force whereby higher current densities may be used.

For a more complete understanding of my invention reference should be had to the accompanying drawing in which Fig. 1 is a vertical section view of an electric furnace embodying my invention, while Fig. 2 is a section view along the line 2-2 of Fig. 1 looking in the direction of the arrows.

Referring to the drawing, in carrying out my invention in one form I provide a refractory crucible 10 which is moulded or otherwise shaped to provide a central reservoir 11 for the charge 12. Communicating with the

reservoir substantially at the bottom thereof on the left hand side are two substantially horizontal ducts 13 and 14. The outer ends 50 of these ducts are connected with a cavity or space 15, substantially at the bottom thereof, in which is placed an electrode 16. The electrode is somewhat smaller than the cavity 15, and is surrounded by the molten charge. 55 Substantially vertical holes or openings 17 and 18 are provided in the refractory crucible 10 having their lower ends communicating with the channels 13 and 14 respectively at points substantially midway of the length of the channels. The upper ends of the holes 17 and 18 are open, and consequently the molten charge 12 rises in the holes and assumes the same hydrostatic head as the charge in the reservoir 11. 65

The opposite or right hand side of the reservoir 12 is similarly arranged, there being two horizontal ducts leading from the reservoir 11 to a cavity or space 19, and two substantially vertical holes or openings 70 connecting with the channels at points substantially midway of the lengths of the channels. Only one of the ducts and holes at the right hand side of the reservoir are shown in the drawing, these being indicated by reference characters 20 and 21 respectively. An electrode 22 is inserted in the space 19 into the molten charge. 75

The crucible 10 may be formed in various ways, for example, by tamping the plastic material from which the crucible is made around a suitably shaped core. Also the crucible may be moulded as a solid block after which the central reservoir 11 and the various cavities and openings connected with it will be cut out of this moulded block. Preferably a metallic protecting and reinforcing casing 23 is provided around the crucible. 85

The electrodes 16 and 22 form a convenient means for conducting an electric current to and from the charge. Obviously any other suitable means for this purpose may be used in place of the electrodes. The electrodes are

electrically connected to a suitable source of electrical supply, such as the low voltage secondary winding of a transformer 24, the primary winding of which is connected to a supply source 25.

In the operation of the furnace the charge is heated by the current passed through it from one electrode to the other. In the starting of the furnace a small quantity of molten charge may be poured in, sufficient to establish the electric circuit between the electrodes, after which additional charge in solid form may be placed in the reservoir 11 and melted. Due to the much smaller cross sectional area of the ducts 13 and 14 and the similar ducts communicating with the opposite side of the central reservoir 11, the current densities in the charge contained in these ducts is much higher than in the other parts of the crucible and consequently heat will be generated in the ducts at a correspondingly greater rate; in fact a comparatively small amount of heat will be generated in the reservoir 12 and in the cavities 15 and 19. It will be observed that the portions of the charge in the substantially vertical holes leading into the horizontal ducts do not carry any current and therefore no heat is generated in the charge contained in these holes.

While the charge is being heated by the current passing through it, it is caused to circulate by the pinch force exerted on the charge in the horizontal ducts, and the hot metal in these ducts is in this manner mixed with the colder metal in the other parts of the furnace. In order to increase the rate of heat generation in the horizontal ducts whereby the rapidity of heating of the charge is increased, it is desirable to use comparatively high current densities in the ducts. The molten charge in the vertical holes acts as an auxiliary supply of molten charge under pressure due to its hydrostatic head, and since this charge is not traversed by the heating current, it is not subjected to the pinch force, and is, therefore, free to flow into the channels and fill any voids which may be formed momentarily due to the effect of the pinch force tending to squeeze off or rupture the charge in the ducts. It is thus possible to successfully operate the furnace with much higher current densities in the ducts than would be possible if the intermediate holes were not provided.

This current density may be many times the density possible without the holes.

In addition to the advantage of much greater rapidity of heating of the charge, a correspondingly more vigorous circulation of the charge is obtained by reason of the increased pinch force. While the pinch force is prevented from opening the electric circuit, it is active in producing circulation so that overheating of the metal in the ducts is prevented, and the charge main-

tained at a substantially uniform temperature notwithstanding the greatly increased rate of heat generation.

While I have described my invention as embodied in concrete form and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claims.

What I claim as new and desire to secure by Letters Patent of the United States, is:—

1. An electric furnace comprising a refractory crucible for the charge provided with a duct in which the charge is heated by an electric current passed through it, and a reservoir providing a hydrostatic head of molten charge communicating with said duct intermediate the ends thereof from which molten charge is supplied to said duct to prevent rupture of the electric circuit by the pinch force acting on the molten charge in said duct.

2. An electric furnace comprising a refractory crucible providing a reservoir for the charge and a duct communicating with said reservoir in which the molten charge is maintained under pressure by the hydrostatic head of molten charge in said reservoir, and means for passing an electric current through the charge in said duct to heat the charge, said crucible being provided with an upwardly extending opening connecting with said duct intermediate its ends into which a portion of the molten charge is forced from said duct by hydrostatic pressure and returned to said duct to prevent rupture of the electric circuit therethrough by the pinch force acting on the molten charge in said duct.

3. An electric furnace comprising a refractory crucible forming a reservoir for the charge and a duct connected to said reservoir substantially at the bottom thereof into which the molten charge is forced by the hydrostatic head of charge in said reservoir, means for producing an electric current in the charge in said duct to heat the charge, and an auxiliary reservoir for the molten charge connected with said duct between its ends into which molten charge is supplied from said duct to be returned to said duct to prevent rupture of the electric circuit therethrough by the pinch force acting on the molten charge in said duct.

4. An electric furnace comprising a refractory crucible providing a reservoir for the charge, a plurality of cavities, ducts connecting said cavities and said reservoir substantially at the bottoms thereof, and substantially vertical openings connecting with said ducts at intermediate points there-

of, electrodes immersed in the molten charge in said cavities, a source of electrical supply connected to said electrodes whereby a current is passed through the molten charge in said ducts to heat the charge, said openings providing hydrostatic heads of molten charge from which charge is supplied under pressure to said ducts to prevent rupture of the electric circuits therethrough by the pinch forces acting on the molten charge in said ducts.

In witness whereof, I have hereunto set my hand this 19th day of February, 1925.

IRVING R. VALENTINE.
